UNITED STATES PATENT OFFICE

2,602,692

HOLD-DOWN FOR BOWS OF COLLAPSIBLE TOPS

Glenn R. Urquhart, Southfield Township, Oakland County, Mich., assignor to General Motors Corporation, Detroit, Mich., a corporation of Delaware

Application November 12, 1949, Serial No. 126,887

12 Claims. (Cl. 296—117)

1

This invention relates to hold-downs for the bows of a collapsible top, particularly the collapsible top in a convertible automobile. It is desirable, when the top of a convertible is lowered, to have the bows tied together so that they will not rattle or abrade one another. This has usually been done by means of straps or a boot. It is the object of the present invention to provide an automatic hold-down which will hold the bows firmly down when the top is collapsed.

Referring to the drawings:

Fig. 1 is a perspective of the inside of a convertible showing part of the bow structure, a hydraulic motor for operating the same, and the new hold-down device. The top is in raised position.

Fig. 2 shows the same parts with the top collapsed and the hold-down engaged with the bow structure to hold it down.

Fig. 3 is a section on the line 3—3 of Fig. 2.

Fig. 4 is a fragmentary plan view showing the hold-down engaging with a bow.

Fig. 5 is an enlarged elevation of the hold-down mechanism showing in dotted lines how the hold-down moves into the operating position.

1 is the main bow of the collapsible top 2. 3 is the control link which is pivoted at 4. This is pivoted to the rear of the rear cant rail section 5. The main bow 1 is connected by linkage with the front cant rail section 7. This linkage, of which the link 6 is a member, may be of varied type. It connects the main bow with the auxiliary center bow 8 and with the front cant rail section 7 which is shown in Fig. 2. Referring to Fig. 2, the auxiliary center bow 8 can be seen in collapsed position. This bow is at 10 pivoted to link 6 which is fastened to the main bow at 11 as shown in Fig. 1. This control link 6 is at its front end, at 12, fastened to a pair of toggle arms 13 and 14, which connects, one (13) with the front cant rail section 7 and the other (14) to the rear cant rail section 5. All the details are not shown in Fig. 2 and are unnecessary for the comprehension of the invention herein involved. 15 is a link that connects the front cant rail section 7 with the auxiliary center bow at 16. The auxiliary center bow 8 has on its knee a pad 17 which is important for the reason that it forms a grasping point or section for the bow hold-down which is the subject matter of this invention.

The hold-down in its inactive position is shown in Fig. 1. It comprises a hold-down or grapple link 18 which is pivoted on the end of bell crank lever 19 by means of pin 20. This link 18 is L-shaped and ribbed to strengthen it. The lower

end has a cam slot 21 through which the stud 22 engages to guide the link and cause it to take a downward and rearward movement as shown by the two dotted line and the one full line view of Fig. 5. This pin 22 is adjustable in slot 52 to alter the fore and aft movement of the grapple link 18. The strip 55 bolted to anchor plate 36 has an offset 54 which guides the ribbed grapple link.

10 The top is automatically raised and lowered by means of a hydraulic or other fluid motor 23 which has the fluid going in or out each end by the tubes 24 and 25. This motor is pivoted at 26 to an anchor piece on the floor pan of the car. The piston (not shown) has a piston rod 27 that connects at 28 with the toggle arms 29 and 30. This connection is at the knee of the toggle arms. One toggle arm 30 is pivoted at 31 to the stanchion 32. The other toggle arm 29 is pivoted at 33 to the main bow 1. When the fluid under pressure comes into the motor cylinder 23 through tube 25 the piston rises and pushes the piston rod 27 outwardly through the top of the motor cylinder to the position shown in Fig. 1. When the piston moves down due to the entry of the fluid under pressure through tube 24, the piston rod 27 retreats into the motor cylinder as shown in Fig. 2. There is a projecting pin 34 at the knee of the activating toggle arms which engages turned over flange 35 of the bell crank lever 19. This pin is eccentric to the bolt on which it is located (Fig. 5) so that its position may be adjusted to alter the timing of the pin striking the shelf. This lever 19 is doubled back on itself (see Fig. 3) and straddles the anchor plate 36 to which it is pivoted by the bolt 37. Hence when this turned over flange or shelf 35 is struck by pin 34 as seen in Fig. 5, the pin travels from the dotted line position shown in this figure to the full line position and thereby causes the bell crank lever 19 to swing on pivot bolt 37 from the dotted line position to the full line position. This carries the grapple link 18 from the dotted line position to the full line position and the hook 38 grasps the pad 17 of the auxiliary bow 8 and pulls down on the bow structure. The nub 40 on the end of the bell crank lever 19 pushes back the block 41 on the spring latch arm 42 which is fastened to the stanchion 43. The nub 40 snaps behind block 41 to hold the hold-down parts in their operating position notwithstanding pressure may be released on the motor piston.

When the pressure in the motor cylinder is released and the piston is caused to travel up-

wardly, the force of the hydraulic power is sufficient to cause the nub of the bell crank lever 19 to snap by the tapered block 41. The bow structure, being under power actuation, will cause the pad 17 to pull the hook 38 upwardly bringing the L-shaped grapple link to the uppermost position in which position the cam slot 21 has an offset 44 on the lower end which allows the pin 22 to travel in this offset and thereby the hooked end of the grapple link will tip forward to completely clear the pad 17.

The rear cant rail section 60, when in its lowermost position, rests against the rubber bumper 45.

What I claim is:

1. A device for holding down the bows of a collapsible top structure such as the top of a convertible automobile, having in combination an anchor plate which can be secured to the body of an automobile, a grapple link, means on said anchor member for guiding the grapple link in an up and down movement and a tipping action toward and away from the bow structure, the top end of the grapple link provided with a hook arranged, when the bows are collapsed, to engage a part on the collapsible bow structure to bear down on the same and hold the bow structure in the collapsed position, a motor having actuating connections with the bows to elevate the same and lower the same, a lever having a part to receive a strike and pivoted to the anchor plate to swing up and down, said lever having its swinging end coupled to the grapple link, an actuating member on the connections between the motor and the bows to strike the strike-receiving part on the lever to move the lever downward when the motor actuated connections pull the bows down, said downward swinging movement of the lever pulling the grapple link downward and tipping the hook to engage the bow structure to hold the same down, and the upward movement of the lever and grapple link being caused by the bows, when they are raised, pulling the hook on the grapple link up with the bows but the guiding means guiding and tipping the link to release the hook from the bow structure.

2. The combination claimed in claim 1 in which the connections between the motor and the bow structure and the actuating member include a piston rod, at the end of which is an actuating pin adapted to strike the strike-receiving part on the lever to pull the lever and the grapple link down when the piston rod moves back into the motor cylinder.

3. The combination claimed in claim 2 in which the activating pin is eccentric on a bolt so that it may be adjusted to alter the time it strikes the part on the lever.

4. The combination claimed in claim 1 in which the grapple link has at its lower end a cam slot engaging with a pin on the anchor plate for guiding the grapple link in its movement toward and down upon the bow structure and in its upward movement up from and away from the bow structure.

5. The combination claimed in claim 4 in which the pin can be adjusted in a slot in the anchor plate to alter the action of the grapple link.

6. The combination claimed in claim 1 in which the grapple link is an L-shaped member connected by a pivot pin with the actuating lever

having at its lower end a cam slot with an offset portion engaging with a pin secured on the anchor plate to guide the link in its movement.

7. The combination claimed in claim 1 in which the actuating lever is an elbow like member having a doubled-over portion straddling the anchor plate to which it is pivoted.

8. The combination claimed in claim 1 in which the actuating lever is an elbow like member having its pivoted end doubled back upon itself to straddle the anchor plate to which it is pivoted, and the doubled back portion flanged to provide the strike receiving part for the pin on the end of the piston rod for actuating the lever.

15. 9. The combination claimed in claim 1 in which a latch member automatically latches the hold-down in the operating position when the hold-down has been operated to engage and hold down the bows.

20. 10. The combination claimed in claim 9 in which the latching member is a spring arm with a tapered block on the end which arm is adapted to be flexed and bent back by the end of the lever when the lever is moved to its hold down position, thereby causing the end of the lever to pass to the other side of the block and the spring arm with the block to snap behind the end of the lever to latch the mechanism in its hold down position.

30. 11. The combination claimed in claim 10 in which the end of the lever has a nub arranged to engage the tapered block on the spring arm to push the spring arm back to cause the block to snap behind the nub when the hold-down is in its lowermost position.

40. 12. A hold-down for holding down the bows of a collapsible top structure such as the top of a convertible automobile, having in combination a movably supported and guided grappling and pull-down iron provided with a cam slot, a stationary pin for support on the body and engaging in the cam slot, a motor provided with an actuating part connected with the bows for thrusting up the bows and pulling them down when the motor is actuated, motion transmitting connections between the actuating part of the motor and the bows and the grappling iron for pulling down the grappling iron to grip the bow structure and hold it down when the actuating part of the motor completes its stroke in pulling down the bows, the grappling iron having an up and down and tilting motion as a result of the combined action of the actuating part of the motor, the transmission connections, and the pin and slot guide so that the grappling iron is brought into engagement with the bows at the bottom of the stroke of the actuating part of the motor and released from the bows at the beginning of the upward stroke of said part.
